CAN PUNCH

John E. Murphy and George W. P. Beckemeier,
Spokane, and Edward C. Couture, Colbert,
Wash., assignors of fifty per cent to Fred N.
Norton, North Richland, Wash.

Application August 15, 1950, Serial No. 179,606

6 Claims. (Cl. 30—6.1)

1

The present invention relates to new and useful improvements in can openers and more particularly to a wall attached can punch for easily and quickly punching a pair of openings in the top of a can.

An important object of the invention is to provide a can punch having a can holder connected to a wall attached bracket by pivoted arms for vertical swinging movement of the can holder and connecting the upper end of the can holder to the bracket by means of a pivoted pressure arm having cutters at its outer end to penetrate the top of the can as the can holder swings downwardly.

A further object of the invention is to provide a novel can punch or cutter construction carried by the pressure plate.

A still further object is to provide a device of this character of simple and practical construction, which is strong and durable, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the can holder in can punching position;

Figure 2 is a longitudinal sectional view showing the can holder in raised position;

Figure 3 is a horizontal sectional view taken on a line 3—3 of Figure 2; and

Figure 4 is a fragmentary perspective view of the outer end of the pressure arm showing the cutters thereon.

Referring now to the drawings in detail wherein for the purpose of illustration I have disclosed a preferred embodiment of the invention, the numeral 5 designates a wall bracket constructed of a metal plate having forwardly projecting flanges 6 at its side edges.

A rod or pin 7 is supported at its ends in the lower portion of flanges 6 and on which an arm 8 is pivoted by means of a forked inner end 9 on the arm. The outer end of arm 8 is formed with an upstanding extension 10 to which a shelf portion 13 of a can holder 14 is pivoted by means of an ear 11 at the underside of the shelf and a pin 12 connecting the ear to extension.

The arm 8 and can holder 14 are supported in a raised horizontal position by means of a coil spring 15 connecting the outer portion of arm 8 to the upper portion of bracket 5.

2

An upper pin 16 is supported in the upper portion of flanges 6 of bracket 5 and a pressure plate or arm 17 has its inner ends welded or otherwise connected to pin 16 for vertical swinging movement.

The upper portion of can holder 14 is formed at its side portions with a pair of upstanding apertured ears 18 in which a rod or pin 19 is pivoted, the rod or pin 19 being welded or otherwise suitably secured to the outer end portion of pressure arm 17.

A pair of cutters 20 project outwardly in a downwardly curved position at the outer end of pressure arm 17, the cutters being formed as integral extensions on the pressure arm, and a brace 21 is welded on top of each cutter and bears against the rod 19. The outer end of the braces taper to match the tapered ends of the cutter.

In the operation of the device, spring 15 holds lower arm 8 and can holder 14 upwardly and the holder is swung downwardly by pressing on the outer edge of shelf 13. Pressure arm 17 swings downwardly with holder 14 to cause cutters 20 to penetrate the top of a can 22 supported on the holder.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A can punch comprising a wall bracket, upper and lower arms pivoted at their inner ends to the bracket for vertical swinging movement, a can holder supported at the outer ends of the arms and pivoted thereto for maintaining a substantially perpendicular position during movement of the arms, and a pair of cutters at the outer end of the upper arm for penetrating the top of a can supported on the holder.

2. A can punch comprising a wall bracket, upper and lower arms pivoted at their inner ends to the bracket for vertical swinging movement, a can holder supported at the outer ends of the arms and pivoted thereto for maintaining a substantially perpendicular position during movement of the arms, a pair of cutters at the outer

end of the upper arm for penetrating the top of a can supported on the holder, and spring means holding the can holder and arms in a raised position.

3. In a can punch, the combination of a vertically swingable can holder and a pressure plate connected to and swingable with the holder and having one end overlying a can supported on the holder, and a pair of downwardly curved cutters carried by the pressure plate at its overlying end for penetrating the can upon a downward movement of the holder.

4. A can punch comprising a lower arm pivoted at one end to a supporting structure for vertical swinging movement, an upper pressure plate also pivoted at one end to the supporting structure above the lower arm, a can holder connected to the outer ends of the arm and pressure plate for movement therewith, and a pair of forwardly and downwardly curved cutters integrally formed with pressure plate at its outer end for penetrating a can held on the holder upon a downward movement thereof.

5. A can punch comprising a lower arm pivoted at one end to a supporting structure for vertical swinging movement, a pressure plate also pivoted at one end to the supporting structure, a can holder pivoted at its bottom to the outer end of the lower arm, a transverse rod fixed on top of the pressure plate at its outer end and projecting

25
30

outwardly at the side edges of the pressure plate to form trunnions to which the top of the can holder is pivoted, and a pair of forwardly and downwardly curved cutters integrally formed with the pressure plate at its outer end and overlying a can supported on the holder to penetrate the top of the can upon a downward movement of the holder.

6. A can punch comprising a lower arm pivoted at one end to a supporting structure for vertical swinging movement, a pressure plate also pivoted at one end to the supporting structure, a can holder pivoted at its bottom to the outer end of the lower arm, a transverse rod fixed on top of the pressure plate at its outer end and projecting outwardly at the side edges of the pressure plate to form trunnions to which the top of the can holder is pivoted, a pair of forwardly and downwardly curved cutters integrally formed with the pressure plate at its outer end and overlying a can supported on the holder to penetrate the top of the can upon a downward movement of the holder, and a brace member fixed to the top of each cutter and braced against the rod.

JOHN E. MURPHY.
